(57) **CLAIM**

I claim the ornamental design for a ramp for a portable sidewalk, as shown and described.

DESCRIPTION

FIG. 1 is a top, front, and left perspective view of the ramp for a portable sidewalk of the present invention.

FIG. 2 is a bottom front and right side perspective view of the ramp for a portable sidewalk of FIG. 1.

FIG. 3 is a top plan view of the ramp for a portable sidewalk of FIG. 1.

FIG. 4 is a bottom plan view of the ramp for a portable sidewalk of FIG. 1.

FIG. 5 is a front elevation view of the ramp for a portable sidewalk of FIG. 1.

FIG. 6 is a rear elevation view of the ramp for a portable sidewalk of FIG. 1.

FIG. 7 is a right side elevation view of the ramp for a portable sidewalk of FIG. 1; and,

FIG. 8 is a left side elevation view of the ramp for a portable sidewalk of FIG. 1.
